UNITED STATES PATENT OFFICE.

EDWARD JANSEN, OF NEW YORK, N. Y.

WALL OR CEILING COVERING.

SPECIFICATION forming part of Letters Patent No. 501,278, dated July 11, 1893.

Application filed August 11, 1892. Serial No. 442,832. (No model.)

To all whom it may concern:

Be it known that I, EDWARD JANSEN, a citizen of the United States, and a resident of the city, county, and State of New York, have invented certain new and useful Improvements 5 in Wall or Ceiling Coverings, of which the following is a specification.

This invention relates to an improved covering for walls and ceilings.

10 The invention consists in the construction and combination of parts and details which will be fully described hereinafter and finally pointed out in the claims.

In the accompanying drawings, Figure 1 is 15 an elevation of a wall provided with my improved wall-covering, the ceiling being in section. Fig. 2 is an enlarged detail-view of a portion of the wall-covering, and Fig. 3 is a vertical transverse-sectional view on the line 20 3 3, Fig. 2.

Similar letters of reference indicate corresponding parts.

The wall A is finished with boards or plaster in the usual manner and is divided by uprights C and horizontal pieces D into panels of various shapes and sizes. The uprights C and the horizontal pieces D are provided with a covering *a* of rattan braiding or weaving, that is, of pieces of rattan woven with warp 25 and weft in the same manner as ordinary fabric, or braided in basket-makers' style. Said rattan covering *a*, is formed around said pieces C and D or is lapped over on the inner sides of said pieces.

30 In the panels formed by the uprights C and the horizontal pieces D, pieces *d* of rattan weaving or braiding are nailed, glued or otherwise fastened to the wall forming the base

or back of said panels and moldings F are then nailed to the edges of the uprights C and horizontal pieces D, so as to cover the joints between the panel fillings *d*, uprights C and horizontal pieces D. 40

The covering in the different panels, uprights and horizontal pieces may be formed 45 of strips of rattan, willow and other basket materials of different widths and these materials may have different colors, so as to break uniformity. The ceilings can be finished in the same manner as the walls. 50

Having thus described my invention, I claim as new and desire to secure by Letters Patent—

1. A wall or ceiling-covering, composed of bars covered with woven or braided reed, rattan, willow or other basket-materials and fastened to the walls or ceilings to form panels and pieces of woven or braided reed or rattan secured to the wall or ceiling in said panels, substantially as set forth. 60

2. The combination, with a wall or ceiling, of strips or bars on the surfaces of which woven or braided reed or rattan is applied, by which bars panels are formed on the wall or ceiling, pieces of woven or braided reed or rattan fastened to the walls within said panels, and moldings fastened along the edges of said bars and lapping over the panel fillings, substantially as set forth. 65

In testimony that I claim the foregoing as 70 my invention I have signed my name in presence of two subscribing witnesses.

EDWARD JANSEN.
